United States Patent Office

Des. 227,407

Patented June 19, 1973

227,407

PAIR OF SPORT SPECTACLES

Vitalino Marchi, Concord, Mass., assignor to Foster Grant Co., Inc., Leominster, Mass.

Filed Feb. 11, 1972, Ser. No. 225,698

Term of patent 14 years

Int. Cl. D16—06

U.S. Cl. D57—1 F

FIG. 2

FIG. 1

FIG. 3

FIG. 1 is a perspective view of a pair of sport spectacles showing my new design;

FIG. 2 is a front elevational view thereof; and

FIG. 3 is a side elevational view thereof.

I claim:

The ornamental design for a pair of sport spectacles, substantially as shown.
